HUGO F. DISSSEL, OF ROCHESTER, NEW YORK

AUTOMATICALLY-OPERATED EXPLOSION DOOR

Application filed October 2, 1928. Serial No. 309,873.

This invention relates to explosion doors and more particularly to the means for automatically opening and closing these doors to allow trains to pass therethru without stopping.

This and other objects of this invention will be apparent from the accompanying drawings, the specification and the appended claims forming a part thereof.

10 In the accompanying drawings:

Figure 1 is a diagrammatic top plan view of a mine tunnel equipped with an explosion door and the automatic means for operating it.

15 Figure 2 is a diagrammatic side elevation of the same mine tunnel, its explosion door and automatic operating means.

Figure 3 is an enlarged side elevation and partial section of the controlling mechanism 20 of one of the controlling valves and the means for operating the explosion door.

Figure 4 is a top plan view of the controlling mechanism illustrated in Figure 3.

Figure 5 is an enlarged sectional view of 25 the check valve used in the air line leading to the apparatus for operating the explosion door.

Mine tunnels are equipped at predetermined points with so called explosion doors 30 in order to protect the stoppings between the tunnels. The use of these explosive doors also enables a mine to be quickly and safely entered after an explosion. These explosion doors must be opened and closed for each train passing thru the tunnel so that a manual operation of these explosion doors delays the movement of the trains as they pass the explosion doors in their movement to and from the workings.

40 The subject matter of my present invention comprises means that automatically operate to open an explosion door on the approach of a train, keep the door open while the train passes and then allow the door to close again after the train has passed the door, as will hereinafter be described.

Compressed air is used in all mines for many purposes and is therefore used in connection with my invention as the medium for 50 the operation of the mechanism. The air is

taken from the compressed air main 1 which is suitably located in the tunnel. Two controlling valves 2 and 3 are used for the opening and closing of the explosion door and are located one on each side thereof at a 55 predetermined distance from it. Each of these valves is connected to the compressed air main 1 by a feed pipe 4. Leading from each of the valves 2 and 3 are the pipes 5 and 6 respectively which meet at the check valve 7 and enter it from opposite ends. The check valve in turn is connected to the cylinder 8 so that on the admission of air into the cylinder thru the check valve, the piston 9 within the cylinder is moved and swings the explosion door open by means of a mechanism that will presently be described.

The controlling valves 2 and 3 are operated to admit air from the air main into the operating cylinder 8 on the approach of the train and more particularly by the flange of each of the wheels of the locomotive and the cars as these wheels roll over the rail 10 of the track. For this purpose the operating valves 2 and 3 are located under the rail 10 on each side of the door and the upper end of the valve stem 11 of each of the controlling valves 2 and 3 is provided with a T head 12. These heads form a pair of ledges on top of each of the valve stems on which the free ends of the swinging inclined levers 13 and 14 are supported. The other ends of the inclined levers are suitably pivoted on the inside of the rail 10 so that as the flange of each wheel approaches and passes over the valves 2 and 3 the levers are rocked and the valve stem 11 is depressed by them thru the T head 12. The levers 13 and 14 are guided in their swinging movement by the guide rail 15 which extends from the pivoted end of one 85 of the levers to the pivoted end of the other of the levers, so that both of the levers are held to a movement in a vertical plane between the guide rail 15 and the rail 10. A sliding connection between the free ends of the levers and the T head 12 of the valve stem 11 is secured by the pins 16, 16 which are carried on the outer ends of the levers and engage suitable slots 17, 17 in the T head.

Each of the valves 2 and 3 comprises a 100

casing provided with a large cylinder 18 and a small cylinder 19. These cylinders are in line with each other with the one cylinder forming a continuation of the other. The 5 valve stem passes thru both of the cylinders and carries the piston valve 20 in the small cylinder and the valve 21 in the larger cylinder. A head 22 closes the bottom of the casing and its large cylinder 18 and a suitable 10 pocket in this head serves as a guide for the lower end of the valve stem 11. An expansion spring 23 surrounds the valve stem between the inside of the head 22 and the valve 21 and its expansive force normally holds this valve 15 against the seat 24 provided by the shoulder that is formed between the large and small cylinder. Air from the pipe 4 is admitted into the large cylinder 18 thru the inlet 25 so that when the valve stem 11 is forced down by 20 the wheel flanges the valve 21 is unseated and allows air to pass into the small cylinder and from there thru the outlet 26 into the pipe 6 and thru the check valve 7 into the cylinder 8.

25 The small cylinder 19 is also provided with a vent opening 27 but this opening is so located that it will be closed by the downward movement of the piston valve and is kept closed while air is admitted from the large cylinder into the small cylinder. However, as soon as the valve stem is no longer depressed by the wheels of the train and the spring 23 forces the valve stem back to its normal position 30 in which the valve 21 is seated, the vent opening 27 is uncovered by the piston valve 20. The air in the cylinder 8 and the piping leading to it can then drain thru the vent opening and allow the piston 9 of the cylinder 8 to 35 move back to its starting position and in so doing allow the explosion door to close as will hereinafter appear.

40 The check valve 7 is provided to prevent air from one valve from flowing into the other valve instead of flowing into the cylinder 8 when but one of the controlling valves is operated by the train as it approaches the explosion door from one side. The check valve comprises a ball 30 located 45 in a horizontal cylindrical valve cage 31 with a valve seat at each end of the cage. The pipes 5 and 6 lead into the ends of the cage 31 and when air is admitted thru but one of the pipes the ball 30 is forced 50 against the seat at the opposite end of the cage and closes the opening leading into the other pipe and the other control valve. The air admitted from one valve can thus only flow 55 thru the openings in the middle of the valve cage of the check valve and into the cylinder 8 connected thereto. On the movement of the piston in the cylinder 8 the door is opened and the train can pass thru the opening in the tunnel that had been closed by it. When the 60 train reaches the valve on the other side of

the door it is of course also operated so that air is then admitted into the check valve from both controlling valves. As the pressure of the air is the same in both valves the flow of air from one valve will however not interfere with the flow of the air from the other until all of the cars have passed over the first valve so that it automatically closes and shuts off the air thru it to the cylinder. The second valve will however keep on admitting air to the cylinder until the last of the cars have passed over it. The door is thus kept open until the whole train has passed the door and will only close after the train has passed the second valve. In this way the pair of controlling valves operate to open the door on the approach of the train from either side and keep the door open until the train has passed it and this without attention from the crew of the train.

85 The connection for the operation of the door by the piston rod of the cylinder 8 comprises a pulley 35 which is carried at the end of the piston rod. A cable or chain 36 extends from one side to the other of the pulley and moves over it as the piston rod with the pulley 35 moves back and forth. One end of the cable or chain 36 is anchored to the wall while the other end is fastened to the door and passes over the guide pulley 37. When 90 the piston rod moves to the left the cable or chain is therefore pulled with it so that the end connected to the door pulls and holds the door open as illustrated in the figures. When the air is allowed to escape from the 95 cylinder after the train has passed the door the piston rod is pulled back to the right into its normal or starting position by means of the cable 38 and the weight which is attached to the free end thereof, thus closing 100 the explosion door after the train has passed.

105 I claim:

1. In an apparatus for automatically opening and closing an explosion door, the combination of a control valve comprising a casing, a pair of cylinders in said casing, a valve stem, a valve carried by said valve stem and adapted to open and close the opening between said cylinders, an inlet into the first of said cylinders, a second valve carried by 110 said valve stem and located within the second of said cylinders, said last named cylinder having a vent opening therein adapted to be opened and closed on the movement of said last named valve, an outlet in said last named cylinder, a source of compressed air connected to the inlet of said first named cylinder, said valve within said first named cylinder being adapted to control the flow of the compressed air from said first named cylinder into said 115 second cylinder and out thru the outlet in said second named cylinder while the vent opening in said second named cylinder is closed by said valve in said second named cylinder.

2. In an apparatus for automatically opening and closing an explosion door, the combination of a pair of controlling valves, a source of compressed air connected to said controlling valves, a check valve housing said control valves being connected to said check valve housing, a ball valve within said check valve housing, a pair of valve seats within said housing with an opening leading from said housing intermediate of said valve seats, the air from the first of said control valves being adapted to seat said ball valve on one of said ball seats and prevent air from escaping into said second control valve, and the air from said second control valve being adapted to force said ball valve to seat on the other of said valve seats and prevent air from escaping into said first control valve, a working cylinder connected to the opening intermediate of said valve seat, and means connecting said working cylinder with said door to open said door on the admission of air from either one or both of said control valves.

25 In testimony whereof I affix my signature.
HUGO F. DISSEL.
